VAPOR ELECTRIC DEVICE

Herbert A. Rose, Leonia, N. J., assignor to Westinghouse Electric & Manufacturing Company, East Pittsburgh, Pa., a corporation of Pennsylvania

Application July 9, 1938, Serial No. 218,340

10 Claims. (Cl. 250—27.5)

My invention relates to a vapor electric device and particularly to vapor condensers for a make-alive type converter.

In the operation of vapor-electric devices such as rectifiers, having pool type cathodes, and particularly those of the make-alive type, large amounts of mercury vapor are projected from the cathode during the current conducting portion of the cycle. One of the principal difficulties with "make-alive" converters of the more conventional design is due to the inability of the condensing surfaces to dispose of the vapor in phase with current changes. This results in a pronounced tendency for the vapor density to increase during the conducting portion of the cycle so that high vapor density exists even after current zero. The difficulty is manifest in an increase in arc back rate.

It has long been recognized as desirable to condense the vapor as nearly in phase with the decay of current at the end of the current conducting period as is possible in order to eliminate dangers of arc backs or other faults during the non-conducting portion of the cycle.

Many arrangements have been used to accomplish this result, most of which have exposed a cooled surface to the region of the arc discharge, depending upon this surface to accommodate or substantially instantaneously condense any mercury vapor which comes in contact with it. Such schemes have, in general, resulted in some improvement in operation. However, the degree has not been sufficiently satisfactory, the principal reason being that sufficient and simultaneous emphasis has not been placed on the fundamental factors relating to methods for rapidly reducing the vapor density at the termination of the conducting period.

Experiments by various physicists have shown that, in general, a vapor is not condensed with one hundred percent efficiency on cooled surfaces. In other words, a molecule does not necessarily condense on the first impact it makes with the cooled or condensing surface. In fact, some surfaces may require on the average many hundreds of impacts or collisions before condensation takes place. Dirty surfaces, in general, accommodate or condense the vapor much less quickly or efficiently than do clean surfaces.

In arc discharge devices it is practice to maintain all surfaces as clean as is possible. However, contamination is frequently present to such a degree that the condensing efficiency per unit area of vapor condensing surface is greatly impaired. Realizing these conditions, I propose to improve

the operation of electric discharge devices and particularly those of the make-alive type, by introducing large amounts of properly proportioned condensing area in the path normally taken by the expanding vapor and to dispose the individual elements of this area in such way that even though the surface has comparatively poor accommodation for the vapor per unit area, very fast condensation on the whole will be effected by these additional means. Condensation will by these means be made to occur substantially in phase with the current at all times, but particularly at the end of the conducting portion of the cycle.

In apparatus according to my invention, I accomplish this by providing a cooling element, preferably in the form of a nest of cooling coils directly exposed to and preferably directly above the active surface of the cathode area, and dispose the anode in such manner that the ions or current flow between the cathode and anode is substantially across or at right angles to the normal direction of vapor flow. In this way, the vapor stream enters the condenser directly and is condensed either immediately or after collision with a number of the condensing surfaces.

As is well known, the individual atoms in a stream of vapor travel helter-skelter in a manner individual to their energies. However, because of the proximity of the cooling surface to the active cathode area, the general vapor flow is substantially directly from the cathode surface to the cooling elements. In order to permit the vapor to flow directly into the cooling elements with lowest impedance, it is desirable to space the individual cooling elements so as to take advantage of the helter-skelter motions. This is accomplished by the large area and open construction of the condenser.

Recent studies by means of the memnoscopes have shown that arc backs, or backfires, as they are sometimes called, may occur at any time during an inverse half cycle instead of substantially at the end of transition time, as has heretofore been supposed. I believe that the cause of some, if not all, of the backfires occurring at other than the transition time is caused either by bombardment of the anode surface by condensed vapor or by foreign particles driven from the cathode surface and possibly aggravated by Brownian movement of infinitesimally small particles. I believe these particles in striking the anode produce conditions there which under the application of inverse potential results in the production of a cathode spot on the anode in much

the same way as a make-alive electrode produces a cathode spot on a mercury surface when subjected to electric potential. To mitigate the bombardment, I propose to interpose a shield 5 member between the cathode surface and the anode surface so that particles traveling in a straight line from the anode to the cathode will intersect this shield surface.

In the preferred embodiment of my invention, 10 the shield is provided as a cylindrical container substantially enclosing the sides and top of the condenser element, leaving the condenser open only substantially to the cathode surface. If desired, the shield may be insulated from the condenser or even made of insulating material to prevent intermediate attachment of the arc to the shield or the condensing element.

It is, accordingly, an object of my invention to provide a vapor-electric device having a cooling 20 element of large surface directly exposed to the active cathode surface.

It is a further object of my invention to provide a cooling element which will condense the evaporated cathode material substantially in 25 phase with the decay of current at the end of the conducting interval.

It is a further object of my invention to provide a vapor-electric device in which the ion currents are substantially transverse of the vapor 30 current between the active cathode area and the condensing element.

It is a further object of my invention to provide impacts of particles driven from the cathode surface on to the anode surface.

It is a further object of my invention to provide means for preventing intermediate attachment of the arc stream to the condensing or shielding elements.

40 Other objects and advantages of my invention will be apparent from the following detailed description taken in conjunction with the accompanying drawings, in which

Figure 1 is a schematic illustration of a vapor-electric valve embodying my invention;

45 Fig. 2 is a similar view of a modification of a similar valve;

Fig. 3 is a similar modification showing a valve adapted for high voltage discharges;

50 Fig. 4 is a schematic illustration showing another method of securing cross flow of the electric current stream and the vapor stream;

Fig. 5 is a schematic illustration showing the manner of condensing vapor on a simple cooled 55 surface; and

Fig. 6 is an illustration of the manner of condensing the cathode vapor in my improved condensing element.

In the illustrated embodiment of my invention 60 according to Figure 1, the electron valve or vapor-electric converter comprises a container 1 preferably constructed of metal and being highly evacuated. A vapor producing element illustrated as a reconstructing cathode 2, which may be composed of mercury, gallium or other suitable material, occupies all or at least the major portion of the bottom of the container 1. The side walls of the container 1 may be cooled by any suitable means herein illustrated as cooling coils 3 attached to the outer surface of the container 1. Cooperating with the cathode 2 is a suitable anode 4 herein illustrated as an annular ring disposed laterally of the active portion of the cathode surface. A suitable make-alive electrode 6, that is, an electrode composed of suitable

high resistance or substantially non-conducting material capable of reducing the negative reluctance of the cathode for creating a cathode spot thereon upon the passage of electric current from the electrode to the cathode, is disposed in permanent contact with the cathode surface, at least during normal operation of the device. Directly above the active cathode surface is my cooling element 10, herein illustrated as being composed of a large number of coils so arranged as to have an opening for allowing access of vapor to the interior of the coil and the individual coils being so arranged that vapor reflected from or re-evaporated from any coil is so directed as to immediately thereafter contact with the same or another portion of the cooling element 10. This multiplicity of cooling surfaces substantially instantly condenses the evaporated cathode material regardless of any impairment of the accommodation coefficient of the individual surface area for any reason. In the embodiment according to Fig. 1, I have shown the anode 4 as being supported at a plurality of points on its periphery, one or more of these points being electrical connectors 11 passing in insulated relation to the evacuated container 1.

In the modification according to Fig. 2, I have shown my anode 4' having a single point of support 11' with the make-alive electrode 6 being brought in through the bottom of the container 1 and suitably insulated from the cathode 2 through which it passes. As in Fig. 1, the cooling element 10 comprises a nest of cooling coils directly exposed to the active cathode surface. In order to prevent direct impingement on the anode 4' by particles driven off from the cathode 2, a suitable shield 15 herein shown as a cylindrical element closed at the top is placed around the condensing element 10. The bottom of the shield 15 is so positioned, with respect to the active anode face and a barrier 16 defining the active cathode surface, that a straight line between the active cathode surface and the anode surface will be intercepted by the shield 15. If desired, this shield 15 may be insulated from the condensing element by suitable insulators or the shield itself may be made of suitable insulating material so that the arc between the cathode 2 and anode 4' cannot attach to the shield element 15.

In the modification according to Fig. 3, the anode 20 has been placed above the cooling element 10 and at a material distance from the cathode 2 in order to adapt the device for high voltage discharges. A suitable shield 21 is placed at least across the top of the condensing element 10 so that the arc discharge from the anode 20 to the cathode 2 must necessarily pass around the condensing element 10 and thus enter the cathode 2 at a direction transverse of the flow of vaporized cathode material. Because of the excessive distance between the anode 20 and the cathode 2, an auxiliary exciting electrode 22 is preferably introduced between the cathode 20 and the anode 2 so that after the exciting of the device by the make-alive electrode 6, an arc will be struck to the auxiliary exciting electrode 22 to provide sufficient ionization to permit ready pick-up of the arc between the main anode 20 and cathode 2. Any suitable means (not shown) may be utilized for maintaining the auxiliary electrode 22 inactive during the non-conducting period in the valve.

In the modification according to Fig. 4, a non-symmetrical form of arrangement is illustrated,

the cathode spot being struck at one end of the cathode 2 in the container 1 while the anode 25 is placed at the other end laterally of the cathode surface and a suitable shield 26 interposed between the anode 25 and cathode 2, said shield 26 being so arranged as to intercept any particles passing in a straight line from the cathode 2 to the anode 25. That portion of the container 1 directly above the cathode 2 is again 10 provided with any suitable multi-surface condenser 10.

The schematic illustration according to Fig. 5 illustrates the manner of condensing evaporated material on the usual cooled surface, the molecules 30 passing from the cathode surface 2 directly to the cooled surface 31. However, in this arrangement, only the layer of molecules adjacent the cooled surface has a chance to be condensed and the molecules of this layer must 20 either be condensed or reflected back into the converter before any further molecules have a chance to be condensed. Because of the impediment of condensation by the molecules adjacent to the condensing surface, it has been found 25 that there is considerable time lag between the decay of current at the end of the conducting portion of the cycles and the condensation of the evaporated cathode material. With my improved condensing element, as shown in Fig. 6, the very 30 large condensing area is provided and is so broken up that a major portion of the evaporated cathode material will impinge directly upon some portion of the condensing surface 10 and if reflected or re-evaporated from this condensing surface will immediately come in contact with another condensing area as shown at 40 so that even though the accommodation coefficient of any particular area of the condenser 10 may be small, the arrangement is such that 40 many collisions take place in a short time so that condensation of the evaporated material is substantially in phase with the decay of current at the end of the conducting portion of the cycle.

While for purposes of illustration, I have 45 shown and described specific modifications of my invention, it will be apparent that many changes and modifications can be made therein without departing from the true spirit of my invention or the scope of the appended claims.

I claim as my invention:

1. A vapor-electric device comprising an evacuated container, an annular anode in said container, a vaporizable cathode in said container, a make-alive electrode in contact with said cathode during normal operation of said device, means for retaining the cathode spot on a predetermined portion of the cathode surface, a nest of cooling coils directly above the active cathode surface and extending through the opening in the annular anode, and a metallic shield enclosing the nest of cooling coils on all sides except that directly exposed to the cathode.

2. A vapor-electric device comprising an evacuated container, an annular anode in said container, a vaporizable cathode in said container, a make-alive electrode in contact with said cathode during normal operation of said device, means for retaining the cathode spot on a predetermined portion of the cathode surface, a nest of cooling coils directly above the active cathode surface and extending through the opening in the annular anode, and a metallic shield enclosing the nest of cooling coils on all sides except that directly exposed to the cathode, said

shield extending to a point such that a straight line passing over the spot retaining means and under the shield will not intersect the anode surface.

3. An electric valve device comprising a metallic container, a vaporizable cathode in said container, means for periodically initiating a cathode spot on said cathode, a barrier for restricting the cathode spot to a predetermined portion of the cathode surface, a nest of cooling coils directly above the cathode and extending beyond the cathode spot barrier, a single anode displaced laterally of said cathode and said nest of cooling coils and a shield for intercepting material which tends to pass directly between the cathode and the anode.

4. A vapor electric device comprising a metallic container, a pool of cathode material covering at least a portion of the bottom of the container, an electrode of resistance material in contact with the cathode pool during normal operation of the device, a baffle for restricting the cathode spot to a predetermined area of the cathode pool, an annular anode having an opening greater in extent than the active cathode 25 area, a nest of cooling coils extending through the opening in said annular anode and directly opposed to the active cathode area.

5. A vapor electric device comprising a metallic container, a pool of cathode material covering at least a portion of the bottom of the container, an electrode of resistance material in contact with the cathode pool during normal operation of the device, a baffle for restricting the cathode spot to a predetermined area of the cathode pool, an annular anode having an opening greater in extent than the active cathode area, a nest of cooling coils extending through the opening in said annular anode and directly opposed to the active cathode area, and a shield 30 substantially enclosing the nest of cooling coils except that portion opposed to the active cathode area.

6. A vapor electric device comprising a metallic container, a pool of cathode material covering at least a portion of the bottom of the container, an electrode of resistance material in contact with the cathode pool during normal operation of the device, a baffle for restricting the cathode spot to a predetermined area of the cathode pool, an annular anode having an opening greater in extent than the active cathode area, a nest of cooling coils extending through the opening in said annular anode and directly opposed to the active cathode area, a shield 45 substantially enclosing the nest of cooling coils except that portion opposed to the active cathode area, and means for insulating said shield from said nest of cooling coils.

7. An electric valve comprising an evacuated container, a vaporizable cathode in said container, means for periodically initiating a cathode spot on said cathode, a baffle for restricting the cathode spot to a predetermined portion of the cathode surface, a cooling element placed directly above the cathode, an annular anode surrounding the cooling element, said annular anode having a central opening larger than the active cathode area and a shield for preventing direct passage of particles from the cathode to the 55 anode surface.

8. An electric valve comprising an evacuated container, a vaporizable cathode in said container, means for periodically initiating a cathode spot in said cathode, a baffle for restricting the 60

cathode spot to a predetermined portion of the cathode surface, a cooling element placed directly above the cathode, an annular anode surrounding the cooling element, said annular anode having a central opening larger than the active 5 cathode area and a shield for preventing direct passage of particles from the cathode to the anode surface, said shield being insulated from said anode and said cathode.

9. An arc-discharge device comprising a container, a vaporizable electrode in said container, a make-alive electrode in contact with said vaporizable electrode during normal operation of the device, a multi-surfaced cooling element directly exposed to said vaporizable electrode, a 10 second electrode cooperating with said vaporizable electrode, said second electrode being placed at one side of said vaporizable electrode and said

cooling element so that the arc discharge between said electrodes flows transversely of the vapor flow between said vaporizable electrode and said cooling element.

10. A vapor-electric device comprising a vaporizable cathode, a single anode cooperating with said vaporizable cathode, a make-alive electrode associated with said vaporizable cathode, a nest of multi-surfaced cooling elements positioned to receive the vapor rising from said vaporizable cathode, said cooling elements being spaced from each other so that vapor readily enters between the cooling surfaces and said cooling surfaces being laterally offset in staggered relation to each other so that the vapor is directed from surface to surface until condensed. 15

HERBERT A. ROSE.
